(57) **CLAIM**

The ornamental design for a baseball box, as shown and described.

DESCRIPTION

FIG. 1 is a front, right and top perspective view of a baseball box, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the baseball box in an open state. The broken lines shown in the drawings are included for the purpose of illustrating portions of the baseball box that form no part of the claimed design.

1 Claim, 9 Drawing Sheets
